UNITED STATES PATENT OFFICE.

JAMES M. BOYLE, OF NEW YORK, N. Y., ASSIGNOR TO MONOLITHIC DUCT COMPANY, A CORPORATION OF NEW YORK.

APPARATUS FOR CONTINUOUSLY MAKING MONOLITHIC OBJECTS.

No. 857,586.

Specification of Letters Patent.

Patented June 25, 1907.

Application filed February 20, 1907. Serial No. 358,425.

To all whom it may concern:

Be it known that I, JAMES M. BOYLE, a citizen of the United States, residing at New York, in the county of New York and State of New York, have invented a certain new and useful Improvement in Apparatus for Continuously Making Monolithic Objects, of which the following is a specification.

The invention relates to continuous monolithic objects such as conduits, and consists in means, as hereinafter set forth, for continuously making said objects of plastic material capable of hardening or setting in a trench or other mold and simultaneously embedding therein a removable core, and also if desired, bars, strips or wires of reinforcing material.

In the accompanying drawing—Figure 1 is a vertical section of a trench and mold therein and the apparatus in place, showing a portion of the completed conduit. Fig. 2 is a cross section on the line *x* *x* of Fig. 1, looking in the direction of arrow *A*. Fig. 3 is a front elevation of the receptacle 4 in the direction of arrow *B*. Fig. 4 is a section on the line *y* *y* of Fig. 1, with the core removed, thus showing the conduit in completed state.

Similar numbers of reference indicate like parts.

In the trench 1, Fig. 4, I dispose side boards 3, forming a trough shaped open mold.

4 is a receptacle for the plastic material of which the conduit is to be formed mounted on trucks 5 for which the upper edges of the side boards 3 serve as rails, so that by means of the cord 6 carried to any suitable stationary winding apparatus 7, said receptacle can be moved in the direction of the arrow *C*. The receptacle 4 has a hopper portion, the front inclined wall 9 of which extends to the bottom of the mold. At its lower edge said wall is flanged rearwardly for a short distance as shown at 10. The angle is preferably somewhat rounded, so that the flange serves to smooth the surface on which it rests, as the receptacle is drawn forward. The rear wall 11 of the hopper is also flanged rearwardly at 12. The height of the horizontal flange 12 above the bottom of the mold determines the vertical thickness of the molded conduit, and the lower face of flange 12 serves to smooth the upper surface of the plastic mass as the receptacle 4 is drawn

ahead. The rear edge of flange 12 is preferably curved upwardly. 55

Extending through the front wall 9 of the receptacle is a metal tube 14. The bottom portion of the rear end of said tube is cut away as shown at 15. The protruding front end of said tube is preferably somewhat flared.

16 is a distensible core of flexible material which passes freely through the tube 14. One end of said core is closed by a plug or 65 any other suitable means, as shown at 17, and the other end also plugged communicates by a hose 18 with any suitable source of air pressure indicated at 19. Also in the front wall 9 are openings 13 for the reception 70 of wires or flexible bars 20 of metal or other reinforcing material to be embedded in the completed conduit. Said openings are here shown in two groups respectively disposed above and below the tube 14. Their number and arrangement may, however, be varied as desired.

The operation of the device is as follows: The end of the trench and side boards being closed, the receptacle 4 is placed there, as indicated by dotted lines, Fig. 1. The end of the distensible core is secured in place in any suitable way, as for example, by a bolt 21 extending from the end plug through the end mold board 22, and set up by a nut on 85 the outside. The core is then distended by air from the source 19. The reinforcing bars or wires 20 which may be secured at their ends in said end board 22 are carried through and are loosely received in the openings 13. 90 The lengths of core and reinforcing bars in advance of the receptacle are extended on the bottom of the mold.

The plastic material to be molded is shoveled into the hopper of receptacle 4, until it 95 rises in the mold to the upper flange 12. Then the winding device 7 is operated to draw the receptacle 4 ahead moving along the reinforcing bars 20 and core 16 and the introduction of plastic material continuing. 100 Obviously, as the receptacle 4 goes forward, the plastic material is deposited in the mold to the proper depth, regulated by flange 12, and portions of the reinforcing bars 20 and core 16 in rear of said receptacle remain embedded in the mass. When the desired length of conduit has been completed, the receptacle 4 is removed from the trench and 105

the core 16, after removal of the distending fluid, is taken out. In this way I am enabled to make monolithic reinforced conduits, continuously and of any length desired. The 5 reinforcing wires or bars can, of course, be omitted.

The term "reinforcing material" as used herein, means any material, such as metal, which when embedded in the plastic mass, 10 strengthens it.

The term "plastic material" means any plastic mass capable of retaining its shape by setting.

I claim:—

15 1. In combination with a stationary open mold of trough shaped cross section, means movable along the length of said mold for depositing plastic material therein, and means for simultaneously laying a continuous flexible core in the material so deposited.

20 2. In combination with a stationary open mold of trough shaped cross section, means movable along the length of said mold for depositing plastic material continuously 25 therein, and means for simultaneously embedding a strip of reinforcing material and a continuous core in the plastic mass.

30 3. In combination with a stationary open mold of trough shaped cross section, means movable along the length of said mold for continuously depositing plastic material therein, means for simultaneously embedding a continuous hollow core of flexible material in the plastic mass, and means for distending said core by internal fluid pressure.

35 4. In combination with a stationary open mold of trough shaped cross section, a hopper movable along the length of said mold, constructed to deliver plastic material into said

mold and having one wall extending to the 40 bottom of said mold: the said wall having an opening for receiving a continuous flexible core.

5. In combination with a stationary open mold of trough shaped cross section, a hopper 45 movable along the length of said mold, constructed to deliver plastic material into said mold and having one wall extending to the bottom of said mold: the said wall having a central opening for receiving a continuous 50 flexible core and a plurality of adjacent openings for receiving strips of reinforcing material.

6. In combination with a stationary open mold of trough shaped cross section, a hopper 55 movable along the length of said mold and constructed to deliver plastic material into said mold: the said hopper having one wall extending to the bottom of said mold provided with an opening for a flexible core, 60 and the other wall having an outwardly turned flange.

7. In combination with a stationary open mold of trough shaped cross section, a hopper constructed to deliver plastic material into 65 said mold and having its front wall downwardly extending to the bottom of said mold, trucks supporting said hopper, guide rails on the mold edges for said trucks, a guide tube in said front hopper wall, and a 70 flexible core extending through said guide tube.

In testimony whereof I have affixed my signature in presence of two witnesses.

JAMES M. BOYLE.
